UNITED STATES PATENT OFFICE.

HERMANN LÖHNERT, OF BROMBERG, PRUSSIA, GERMANY.

MACHINE FOR HULLING CLOVER.

SPECIFICATION forming part of Letters Patent No. 248,937, dated November 1, 1881.

Application filed June 22, 1881. (No model.) Patented in Belgium November 3, 1879, in Germany March 20, 1880, and July 20, 1880, and in Austria April 19, 1880, and September 28, 1880.

To all whom it may concern:

Be it known that I, HERMANN LÖHNERT, residing at the city of Bromberg, in the Kingdom of Prussia, German Empire, have invented 5 Improvements in Machines for Hulling Clover, of which the following is a specification.

This invention relates to improvements in clover-hullers of that class in which a fixed horizontal, or nearly horizontal, hulling cylinder or drum is used in connection with a rotating agitator, by which the hulling of the clover-seed is obtained as a result of the friction of the heads along the inner roughened surface of 15 the drum. The hulling of the clover is to some extent dependent upon the degree of moisture of the clover-heads which contain the seed. The drier the heads the easier it is to remove the seed. Moist clover-heads have consequently 20 to be exposed for a longer time to the action of the machine than dry ones. This necessitates for dry clover a less length of drum than for moist clover, as otherwise, with a uniform length of drum, in one case more than 25 necessary work would be performed, while in the other case the seed would not be entirely extracted. As it would not be practicable to construct for each degree of moisture of the clover-heads a separate machine, it is more 30 advantageous to construct the hulling-machine of a certain length and to surround the different sections of the hulling-drum at the lower part with shell-sections which can be removed or applied as the case requires, so as to expose 35 the clover-heads for a greater or less length of time to the action of the machine.

In the accompanying drawings, Figure 1 is a vertical transverse section of my improved clover-hulling machine; Fig. 2, a vertical longitudinal section of the same on line *x*, *x*, Fig. 1; Fig. 3, a detail side view of the hulling-drum; Fig. 4, a detail vertical transverse section of the drum and beater; and Fig. 5 is an enlarged view of a part of the wire screen employed for the lower half of the hulling-drum.

The same letters of reference indicate the same or corresponding parts.

Referring to the drawings, A represents a 50 fixed cylindrical hulling-drum, which is sup-

ported in a horizontal, or nearly horizontal, position at the inside of an inclosing wooden frame, B. The outer frame, B, is provided with hinged side doors for readily getting at the drum A and removing the hulled clover-seed. The frame B is closed at the top, sides, and ends by means of tightly-fitting boards, so as to prevent the escape of dust from the frame. Upon transverse end pieces of the frame B are supported the journal-bearings for the shaft C 60 of the beater D, which shaft extends longitudinally through the entire frame and carries at one end a pulley, to which the transmitting-belt for operating the beater is applied. Upon the shaft C are keyed a number of spider-frames, D', the arms of which support at their outer ends the beater-strips D², which take up and throw the clover-heads into contact with the hulling-frame. The arms of the spider-frames immediately back of the beaters are 65 steadied by circular braces, as shown in Figs. 1 and 3.

The upper half of the hulling-drum A is made of sheet metal, while the lower half is formed of a wire screen. The drum A is stiffened by exterior rings, A', of T-shaped cross-sections. The wire screen at the lower half of the drum is made of rectangularly-intersecting wire rods of square cross-section, which exert a more favorable frictional influence upon the 80 clover-heads than the common perforated or other screens heretofore in use, and which facilitate the dropping of the hulled seed through the openings of the same. The quick outward passage of the seed from the drum has the advantage that the seed is not injured by being 85 repeatedly thrown against the screen. The drum accomplishes thereby the work of hulling quicker than the perforated sheet-metal drums heretofore employed, and renders the 90 working of the machine easier and less expensive.

The hulling-drum A is divided by means of the exterior stiffening-rings of T-shaped cross-section into three or more sections, the lower 95 parts of which can be opened or closed by means of semicircular removable shell-sections C' C² C³, which are attached to the exterior rings by means of clamps, screws, or in any other suitable manner. When the clover-heads are quite 100

dry only one outer shell, C', is attached below the first section of the drum, as shown in Fig. 2, while the shells C² and C³ are left off. Should the seed not be entirely removed from the heads, 5 the shell C² has to be applied, while with moist heads also the shell C³ has to be attached, as shown in Fig. 4. Should the clover be very dry, which, however, is but very rarely the case, even the first shell may be removed, and therefore 10 by the seed be dropped directly from the first section of the drum.

The clover-heads are fed to the hulling-drum through a hopper, B, with inclined discharge-channels, which extend downwardly to a point 15 near the shaft of the beater. Consequently the heads are fed in a nearly horizontal direction to the drum and instantly taken up by the revolving beater, so as to be thrown against the fixed wire screen forming the lower part of the drum. The clover-heads are continuously fed to the drum and worked up by the machine, which is a considerable advantage as compared 20 with the clover-hullers in which the feed-hopper has been arranged vertically at the top of the drum, which not only unnecessarily shortens the beater, but renders it less effective in hulling, as the clover-heads have been partly thrown up again by the revolving beater. The same construction of hulling-drum with lower 25

screened half and an interior rotating agita- 30 tor is also adapted for use in common thrash-ing-machines, to which application special ref-erence is made, as it is deemed to be fully with-in the scope of this invention.

Having thus described my invention, I claim 35 as new and desire to secure by Letters Patent—

1. In a clover-hulling machine, the combina-tion, with a fixed hulling-drum, the lower half 40 of which is formed of wire screen, of an inter-ior revolving beater and exterior sectional and removable shells, which are adapted to be attached to or removed from the screen por-tions, substantially as set forth.

2. In a clover-hulling machine, the combina-tion of a fixed hulling cylinder or drum, having 45 an upper imperforate and a lower wire screen half, and exterior stiffening-rings, with an inter-ior revolving beater and with exterior sheet-metal shell-sections, which are attached to or removed from the stiffening-rings of the drum, 50 for the purpose specified.

In testimony whereof I have signed my name to this specification in the presence of two subscribing witnesses.

HERMANN LÖHNERT.
